UNITED STATES PATENT OFFICE.

ROY A. GRAMSE, OF PADUCAH, KENTUCKY, ASSIGNOR TO SOUTHERN TEXTILE MANUFACTURING CO., OF PADUCAH, KENTUCKY, A CORPORATION OF KENTUCKY.

STOP MECHANISM FOR SEWING MACHINES.

Continuation of application Serial No. 731,295, filed August 11, 1924. This application filed June 20, 1927. Serial No. 199,967.

My invention relates to improvements in stop mechanism for sewing machines, the present embodiment of the invention being particularly designed and adapted for use 5 in connection with that class or type of sewing machines commonly known as "dial loopers".

The primary object of the invention is to provide a generally improved stop motion 10 of the type indicated, which will be exceedingly simple in construction, as well as efficient and reliable in use,—the parts being so arranged and disposed relative to each other and to the adjacent working parts of 15 the machine to which it is attached as to reduce the liability of disarrangement or breakage to a minimum.

A further and very important object is the provision of an improved stop motion at- 20 tachment which may be readily attached to or detached from the ordinary or conventional form of dial looper without in any way interfering with the normal operation of the latter, including in particular im- 25 proved clutch shifter mechanism controlled by the thread for shifting the clutch shift mechanism to an open or "stopped" position.

A further object of the invention is to provide a control for the clutch shifter mech- 30 anism which will be normally maintained in inoperative position but which will be rendered operative to shift the clutch shifter mechanism to an open or "stopped" position either upon breakage or depletion of the 35 thread or upon the occurrence of a knot in the thread.

A still further and important object is the provision of an improved knot catcher ar- 40 ranged in co-operative relation to the thread tension and sewing mechanism, said knot catcher being provided with an improved form and arrangement of thread intercepting and deflecting means adapted upon the occurrence of a knot to intercept and move 45 the thread to one side, thereby releasing the thread control or trip mechanism to positively move the stop mechanism to release the machine driving parts.

With the above mentioned and other ends 50 in view, the invention consists in the novel

construction, arrangement and combination of parts, hereinafter described, illustrated in one of its embodiments in the accompanying drawings, and particularly pointed out in the appended claims.

55

Referring to the drawings, forming a part of this specification,—

Figure 1 is a top plan view of a sewing machine of the dial looper type, equipped with stop mechanism constructed in accordance with this invention, the old or conventional machine parts being shown in dotted lines.

60

Fig. 2, a top plan view of the thread and cam controlled shiftable link adapted in one position to clear the driving and clutch shifting mechanism and in another to connect therewith and shift the clutch shifting mechanism to an open position.

65

Fig. 3, an end elevation of said thread and cam controlled shifter link, detached, as in Fig. 2.

70

Fig. 4, a top plan view of a dial looper equipped with the improved stop mechanism and showing the parts in their connected 75 fully shifted clutch released position, as upon the occurrence of a knotted or broken thread.

Fig. 5, an enlarged side elevation of the improved oscillatory knot catcher and thread 80 guide and shift mechanism in association with the conventional thread catcher mechanism, and in normal sewing or untripped position.

85

Fig. 6, a front elevation of the same.

Similar numerals of reference designate like parts throughout all the figures of the drawings.

In Figs. 1 and 4 of the drawings, I have shown my improvements applied to a sewing machine of the dial looper type embodying the usual bed plate 1, together with the usual overhanging dial supporting arm 2. The machine is provided with suitable driving and clutch shifting mechanism, consisting, in the present instance, of a driving shaft 3, mounted upon the bed plate 1 and extending through the base portion of the arm 2 at right angles thereto.

90

95

The clutch driving mechanism comprises 100

relatively circumferentially fixed and movable clutch members 4 and 5, respectively on the end of the driving shaft 3, the longitudinally movable circumferentially fixed clutch 4 being adapted to be moved or shifted by means of a slide or shift member 4^a, operating in a sleeve or guard member 6, and provided with spaced bearing members 4^b, adapted to be positively moved to and from the respective engaged and disengaged positions by means of an interposed cam 7, horizontally movable on a suitable bearing, the cam 7 being provided with an actuating arm or lever 7^a.

15 The clutch shifter mechanism includes a longitudinally movable clutch shifter 8, consisting, in the present instance, of a shifter rod extending forwardly and parallel with the overhanging arm 2 and supported in a suitable guide bracket 9.

As a means of positively actuating the clutch shifter mechanism, when the stop mechanism hereinafter referred to is brought into action, the driving shaft 3 is provided at one side with a drive wheel 10 which, in the present instance, is in the specific form of a rotary channel shaped member having a driving pin or projection 10^a. The clutch shifter member or rod 8 is also provided with a sleeve or projection 8^a, having a stud member 8^b to be engaged by the thread controlled link of the stop mechanism when said link is engaged by the abutment or projection 10^a, as hereinafter referred to.

35 As a means of providing a link device adapted in one position to clear the said driving and clutch mechanism and in another to connect therewith and shift said clutch mechanism to open the clutch and stop the driving mechanism and the various devices connected therewith, a longitudinally and transversely movable link 11, is provided, the body of said link, in the present instance, being in the specific form of a rod or shaft 11 carried in suitable bearings 12^a, of a supporting and attaching plate 12. The plate 12, in the present instance, is attached to the top of the overhanging arm 2 by means of attaching elements or screws 12^b. The rod or link 11 is loosely mounted in the bearings 12^a so that it may be readily moved longitudinally, as well as rocked or tilted through the control arms or levers now described. The relatively movable or pivotable link 11 is provided at one end with a depending arm or lever 11^a (see Fig. 3) and at the other end with a horizontally extending arm or lever 11^b, the latter extending above the clutch shifter 8 and in suitable proximity to the sleeve 8^a and projection 8^b to engage the latter when tilted by the thread controlled trip mechanism, hereinafter referred to.

65 As a means of holding the link 11 with its arms 11^a and 11^b in a neutral position

with respect to the driving and clutch shifter mechanism during the normal sewing operation, suitable thread controlled or trip mechanism is provided consisting, in the present instance, of a cam member 13, pivotally mounted at one side of the attaching plate and arranged to engage beneath the arm 11^b and in the normal position adapted to sustain the arm 11^b with the arm 11^a in a neutral position (see Fig. 1) and in another position to be engaged by the projection 10^a and to engage and shift the clutch shifter 8, as shown in Fig. 4 of the drawings. The cam 13 may be of any suitable form and, in the present instance, is formed as an off-set portion of a shaft 13^a, mounted in bearings 12^c, of the plate 12, said cam or shaft being provided with a horizontally extending arm 13^b, having its free end normally sustained by the thread 14, after passing through the tension device or disc 15, arranged on the disc stud 16. The thread tension device may be of the usual construction, as shown, and mounted on the usual tension post or pedestal 17. The thread 14 after passing through the tension disc 15 and through an opening or eye 18^a of a post or stud 18 is led from the tension disc 15 over a thread guide 19, after which it is passed down to the sewing mechanism and by being so arranged a horizontally extending taut portion 14^a is maintained between the thread tension and thread guide mechanism for conveniently supporting the thread controlled arm 13^b.

As a means of causing the trip arm 13^b to drop and thereby bring the stop mechanism into use when a knot or enlarged or obstructing portion occurs in the thread, a thread controlled knot catcher and trip device is provided, said device, in the present instance, comprising an oscillatory member 20, carried in a pivoted block 21, loosely mounted on the stud shaft 16, the member 20 being provided at one end with a knot catcher consisting, in the present instance, of a loop head 20^a, having a vertical slot 20^b to readily receive the thread 14. As a means of engaging and deflecting the taut thread portion 14^a away from the thread sustained trip arm 13^b in the event that a knot comes into engagement with the knot catcher and as the latter swings downwardly, the thread controlled or actuated member 20 is provided at one end and near the arm 13^b with an arm or upwardly and outwardly inclined thread intercepting and moving element 20^c, which upon moving upwardly will deflect the thread, thus clearing the end of the trip arm 13^b and allowing the latter to drop. Should a break in the thread occur, the looseness in the thread in proximity to the trip arm 13^b will obviously allow the latter to drop and function, as above described, likewise upon depletion of the 130

thread the trip arm 13^b will be permitted to drop and thus render the stop mechanism operative.

This is a continuation of application 5 Serial No. 731,295, filed August 11, 1924.

I claim:

1. In combination with the drive and drive control mechanism of a sewing machine, of stop motion mechanism including 10 a thread control knot catcher and trip device, said trip device being operable by said knot catcher and upon depletion of the thread, said trip device being normally supported by the thread and movable to operative position by gravity.

2. In combination with the drive and drive control mechanism of a sewing machine, of a stop motion mechanism including a normally inoperative trip device, said 20 trip device being rendered operable by the presence of a knot in the thread and upon breakage or depletion of said thread said trip device being normally supported by the thread and movable to operative position by 25 gravity.

3. In a sewing machine, the combination 30 of a driving shaft, a clutch mechanism on said shaft, and a stop motion mechanism for rendering said clutch inoperative, said stop motion comprising a shifter mechanism connected to said clutch, a driving mechanism operable by said shaft, and thread engaging means operable by disengagement of the thread therefrom for connecting said driving and clutch shifter mechanisms, and means for deflecting the thread and moving it out of engagement with the last mentioned means.

4. In a sewing machine, the combination 40 of a driving shaft, a clutch mechanism on said shaft, and a stop motion mechanism for rendering said clutch inoperative, said stop motion comprising a shifter mechanism connected to said clutch, a driving mechanism operable by said shaft, a thread engaging trip operable by disengagement of the thread therefrom for connecting said driving and clutch shifter mechanisms, and a knot detector and deflector engaging said 45 thread to effect a deflection thereof and disengage it from said trip upon occurrence of a knot therein.

5. In a sewing machine, the combination 50 of a driving shaft, a clutch mechanism on said shaft, and a stop mechanism for rendering said clutch inoperative, said stop mechanism comprising a clutch shifter mechanism, a driving mechanism normally disconnected from the shifter mechanism, a connecting member for connecting said driving and clutch shifter mechanisms, and a thread engaging trip, said connecting member being normally maintained in position by said trip to render the clutch shifter in- 55 operable, said trip being rendered operable

by deflection of the thread to disengage it therefrom, whereby said connecting member may be actuated to render the stop mechanism operative, and means for deflecting the thread from said trip upon occurrence of 70 a knot in the thread.

6. In combination with the drive and drive control mechanism of a sewing machine, of stop motion mechanism including 75 a thread controlled knot catcher and trip device, said trip device having an element supported in inoperative position by the thread.

7. In a looping machine, including driving and driving shifter mechanism, driving 80 shifter means controlling said driving shifter mechanism, and a trip mechanism for rendering said means operable during an uninterrupted feed of thread to the machine, said trip being controlled by the position of 85 the thread relatively to an element thereof to support the latter in neutral or inoperative position, and means for moving the thread relatively to the trip element upon occurrence of a knot in said thread.

8. In combination with the drive and drive control mechanism, of a looping machine, including thread tension mechanism therefor, of stop motion mechanism including 90 a thread control device for controlling said drive control mechanism, said thread control device embodying an element normally supported in neutral position by the thread, and means engageable by a knot in the thread for deflecting the said thread and moving it from the position in which it normally supports said element.

9. In a looping machine including driving and clutch shifter and thread tension mechanisms, connections between said driving and clutch shifter mechanisms, and a trip normally maintaining said connections inoperative, said trip being controlled by the tension of the thread and maintained in inoperative position by engagement with the 110 thread and adapted to render said connections operable upon depletion or breakage of the thread as well as upon movement of the thread relatively thereto.

10. In a device of the character described, 115 in combination with the thread tension mechanism of a sewing machine and the driving mechanism therefor, a trip mechanism having an element normally supported in inoperative position by the thread, and a movable knot catcher having an arm adapted to intercept and move the thread to one side of said trip element when a knot occurs therein, whereby said trip will be rendered operable.

11. In combination with a sewing machine including driving and clutch shifter mechanism, a link loosely and pivotally mounted between said driving and clutch shifter mechanism, a taut thread sustained 120 125 130

- and controlled device by which said link is held in a neutral position, said thread sustained and controlled device being movable upon breakage or deflection of the taut thread to permit said link to move into engagement with said driving and clutch shifter mechanisms to thereby disconnect the driving mechanism, and means operable by a knot in the thread for likewise permitting a movement of the thread sustained and controlled device whereby said link will also be permitted to move into engagement with said driving and clutch shifter mechanism.
12. In a machine of the character described, in combination with the driving and thread tension and clutch shifter mechanisms of a sewing machine, a link interposed between said driving and clutch shifter mechanisms, means sustained by the thread for holding said link in a neutral position, said link being free to move to its operative position into engagement with said driving and clutch shifter mechanisms upon depletion or breakage of the thread, and means operable by a knot in the thread to deflect or move said thread with respect to the thread sustained means and render said link free to move to its operative position.
13. In a stop motion device for sewing machines, in combination with the driving and clutch shifter mechanisms thereof, a link normally positioned to clear said driving and clutch shifter mechanisms, said link being movable to connect with said driving and clutch shifter mechanisms, a trip by which said link is maintained in its neutral position, said trip being normally sustained by the thread whereby said trip will be operated and the link moved from its neutral position upon breakage or depletion of the thread, and a knot catcher having a thread intercepting and deflecting element adapted upon occurrence of a knot in the thread to deflect said thread from its normal trip sustaining position and thereby permit movement of the link from its neutral position.
14. In a structure of the character described, a driving shaft provided with a clutch member, a clutch shifter, a wheel on said shaft for actuating said clutch shifter, a pivoted link having arms normally positioned to clear said wheel and clutch shifter, said link and the arms thereof being movable to be engaged by said wheel and clutch shifter to actuate the latter, means for maintaining said link in its neutral position from a taut thread leading to the sewing machine, and a pivoted thread guide including a knot catcher adapted to be actuated by a thread knot to shift said means for maintaining the link in its neutral position and permitting said link to move from its neutral position to an operable or clutch shifter position, thereby effecting a stoppage of the driving shaft and its connections.
15. In a structure of the character described, a driving shaft provided with a clutch member and a driving connection, a clutch shifter, a longitudinally and transversely movable link, levers carried by said link normally positioned to clear said driving connection and clutch shifter but adapted to be moved into engagement with said driving connection and clutch shifter, a thread supported member by which said link is maintained in a neutral position, and a pivoted knot catcher engaging said thread adapted to move the same and permit said thread supported member to release said link and allow the latter to assume a position to engage said projection and clutch shifter.
16. In a device of the character described, a driving shaft having a projection, clutch driving mechanism on said shaft, a thread tensioning mechanism including a movable knot catcher and thread deflector, a clutch shifter, a link movable into and out of engagement with said projection and clutch shifter, a link supporting member and a trip arm connected to said link supporting member and normally supported on the tension thread for maintaining said member and the link in position to prevent engagement of the link with the projection and clutch shifter, whereby deflection of the thread by the knot catcher and thread deflector or breakage or depletion of said thread will result in the removal of the supporting thread for the trip arm and permit the link supporting member and link to assume positions whereby the link will engage the projection and clutch shifter.
17. In a device of the character described, in combination with the driving shaft of a sewing machine including a clutch driving mechanism, and a thread tension device, an oscillatory thread guide and knot catcher, means for shifting said mechanism, a thread supported trip member associated with said thread tension device and thread guide and knot catcher, and means for engaging and rendering said clutch shifter operable, said means being held in neutral position by said thread supported trip member, and said means being movable into connected relation with said driving shaft and said clutch shifter to throw the driving shaft and its connections out of operation upon movement of the thread supported trip member, said trip member being free to move upon breakage or depletion of the thread or upon oscillation of said thread guide and knot catcher.
18. In a device of the character described, a driving shaft having a projection, clutch driving mechanism on said shaft, thread tension mechanism including an oscillatory

thread guide and knot catcher adapted to deflect the thread upon occurrence of a knot therein, a clutch shifter, a cam member having an arm normally supported on the 5 thread carried by said thread guide and tension mechanism, and a pivoted movable link interposed between said driving shaft, projection and clutch shifter, said link being held by said cam member in neutral posi-

tion when said member is in its normally 10 thread supported position and said link being movable to connect said projection and clutch shifter when said thread supported cam member is freed by breakage or depletion of the thread or by deflection of 15 the thread by said knot catcher.

ROY A. GRAMSE.
